CONDENSER APPARATUS

David W. R. Morgan, Warthmore, Pa., assignor to Westinghouse Electric & Manufacturing Company, East Pittsburgh, Pa., a corporation of Pennsylvania

Application July 15, 1938, Serial No. 219,305

8 Claims. (Cl. 60—95)

My invention relates to turbine and condenser arrangements and it has for an object to provide turbine supporting means extending through and embodied as a part of the condenser structure.

In the application of steam turbines to central stations, 3600 R. P. M. turbines are being widely used and there is a tendency to employ two low-pressure turbines in tandem in installations; however, the tandem arrangement makes installation of the condenser difficult because of the necessary bearing, as well as supporting means therefor, between the turbines. While the distance between the turbines may be increased to facilitate provision of the bearing supporting means and the installation of condensers, this would not only increase the turbine cost, but also necessitate increase in size of the shaft and possibly introduce a critical speed problem, and there would also be a condenser for each turbine. The installation of the twin condenser arrangement, the necessary piping, and equalizing connection between the condensers obviously is an expensive one. In accordance with the present invention, I not only provide a single condenser for a turbine installation of this character, but also the arrangement is such that the adjacent ends of the turbines may be arranged close together, the support for the bearing between the turbines being provided by means of column structure or structures embodied in the condenser. A single condenser arranged in this way is more economical and has better performance because of improved steam distribution and the cost is reduced, not only because there is but one condenser, but also on account of the incidental reduced piping cost and the absence of any special equalizing equipment that would be required for twin condensers.

A further object of the invention is the provision of novel supporting means for the main bearing between two low pressure turbines arranged in tandem.

Another object of the invention is the provision of a condenser structure embodying supporting means for its associated turbine or turbines.

Another object of the invention is the provision of a pair of turbines arranged in tandem with a single condenser associated therewith and positioned therebelow, together with supporting means for a common bearing at the adjacent ends of the turbines, the supporting means extending vertically through the steam space of the condenser.

These and other objects are effected by my invention as will be apparent from the following description and claims taken in connection with the accompanying drawings forming a part of this application, in which:

Fig. 1 is a side elevational view of a turbine and condenser aggregate, with a portion thereof broken away for the sake of clearness;

Fig. 2 is a longitudinal sectional view of the apparatus shown in Fig. 1;

Fig. 3 is a sectional view taken on the line III—III of Fig. 2;

Fig. 4 is an enlarged fragmentary view of a portion of the structure illustrated in Fig. 3; and,

Fig. 5 is a fragmentary view of a portion of the structure shown in Fig. 2, and illustrating a modification thereof.

In the drawings, there is shown, at 10, a turbine and condenser aggregate comprised by a pair of low pressure turbines 11, arranged in tandem for driving the single shaft 12, and having their adjacent ends 13 carried by a common transverse support 14. Exhaust steam casings 16 are provided, connecting the turbines with the exhaust steam inlet 17 of the condenser 18, the latter being comprised by a shell 19 having a condensate outlet 20 and a plurality of tubes 21 extending longitudinally through the shell and having their terminal portions mounted in end tube plates 22. Waterbox structures 23 are associated with the end tube plates and are provided with water connections 24. Preferably, an air offtake 25 is disposed concentrically with respect to the tubes 21, and baffles 25a are located at spaced points above and below the air offtake 25 to prevent short-circuiting of the entering steam.

A pair of supporting members or column structures 26 extend vertically through the shell of the condenser adjacent the inner faces of the end tube plates. The lower ends of the columns or supports project below the condenser and are carried by a suitable foundation or footing 27. The upper ends of the columns or supports project above the condenser shell and carry a transverse beam 28 secured thereto in any desirable manner, as by brackets 29. The columns 26 and the beam 28 carry the common transverse support 14 of the adjacent ends 13 of the turbines.

Preferably, the columns 26 are comprised by steel shapes of I or H section, such as shown in Fig. 4, having double flanges 31 adjacent the edge which is disposed in close proximity to the end tube plates 22. The columns not only support the central bearing of the turbines, but together with the casings 16, also carry the weight of the con-

denser by having the end tube plates 22 bolted or otherwise secured thereto. Generally, in installations involving the use of a pair of low pressure turbines, the condenser will be of such size as to require end tube plates made in two or more sections. In such an arrangement, the columns 26 overlie the vertical joint 32 between the two sections of the end tube plate. These sections may be held in place by a plurality of bolts 33 extending through the edges thereof and the overlying flanges 31 of the member 26. Preferably, leakage at the joint and around the bolts is prevented by the provision of a sealing strip 34 and compressible gaskets 36 and 37, the former being disposed between the sealing strip and the tube plate sections and the latter being positioned beneath the nuts on the bolts 33.

To avoid misalignment in the turbine arrangement, due to expansion or contraction of the columns 26, the portion of the latter in the steam space is insulated. Any suitable insulation may be used, such as shown at 39 in Fig. 4.

In Fig. 5, there is illustrated a possible variation of the previously described construction, wherein the columns project above the condenser only a relatively short distance. Any additional length needed for these supports may be provided as a separate unit, and the two secured together in any desired manner, as by lap plates 41. This arrangement permits of manufacture and assembly of the condenser and columns and the independent provision of the remaining supporting structure suitable to the requirements of the particular installation.

35 The arrangement constituting the subject-matter of this invention in nowise lessens the efficiency of the condenser, as the space occupied by the columns is not generally usable for condensing surface since the tube plate must be made in two sections and the vertical joint therebetween provided with a support corresponding roughly to the columns.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

50 What I claim is:

1. The combination with a turbine having an exhaust casing, of a surface condenser having the interior of its shell in communication with said casing, column structures extending vertically across the interior of the shell, said column structures having lower end portions extending exteriorly and below the shell and having upper portions extending exteriorly of the shell and of the exhaust casing, footings for the lower ends of the columns, turbine supporting means carried by the upper ends of the columns, and means for connecting the shell to the exhaust casing.

2. The combination with two turbines in tandem and provided with exhaust casings, of a surface condenser in communication with said casings, means providing a common support for the adjacent ends of the turbines and embodying column structures extending diametrically transversely of the condenser and projecting above and below the latter, and means for connecting the condenser to the exhaust casing and to the column structures for its support therefrom.

3. The combination with a pair of turbines arranged in tandem and having exhaust casings, of a surface condenser in communication with said casings comprised by a shell having an exhaust steam inlet in communication with the turbines and a condensate outlet, tubes extending longitudinally through said shell, a pair of end tube plates supporting the terminal portions of said tubes and water boxes associated with said tube plates; means providing a common support for the adjacent ends of the turbines and embodying a pair of spaced columns extending through the condenser adjacent the tube plates; means for connecting the condenser shell to the exhaust casings and for connecting the tube plates to the columns, whereby the condenser is supported by the turbines and columns.

4. In combination with a pair of turbines arranged in tandem and having exhaust casings; a surface condenser in communication with said casings and disposed therebeneath and comprised by a shell having an exhaust steam inlet communicating with said turbines and a condensate outlet, tubes extending longitudinally through said shell, end tube plates supporting the terminal portions of said tubes and cooperating with the shell to define a steam space; a pair of spaced columns extending through said steam space and the condenser and providing a common support for the adjacent ends of the turbines; means for connecting the condenser to the exhaust casings and to the columns to provide for its support therefrom; and means surrounding the portions of the columns located within the steam space to insulate them from temperature changes.

5. A surface condenser for use with a pair of turbines arranged in tandem and having a common transverse supporting beam for their adjacent ends; comprised by a shell having an exhaust steam inlet and a condensate outlet, a plurality of tubes extending longitudinally therethrough, a pair of end tube plates supporting the terminal portions of said tubes and cooperating with the shell to define therein a steam space, water boxes associated with said end tube plates, and a pair of columns extending through the shell and steam space and positioned substantially concentrically transversely thereof, the lower ends of said columns projecting beyond the bottom of the shell for cooperation with a foundation and the upper ends projecting beyond the top of the shell for cooperation with the turbine transverse supporting beam to support the latter.

6. A structure as specified in claim 5, wherein the columns are located adjacent the end tube plates and are secured thereto to partially support the latter.

7. A structure as specified in claim 5 including means insulating the columns from the steam space.

8. A structure as specified in claim 5 wherein each tube sheet is comprised by at least two sections providing a vertical joint transversely aligned with the columns, and each of the pair of columns is comprised by a steel shape having a double flange overlying the tube sheet sections adjacent the joint, and means securing the tube sheet sections to the overlying flanges of the columns.

DAVID W. R. MORGAN.
